UNITED STATES PATENT OFFICE.

HARRY STEHMANN, OF BERLIN-HOHENSHONHAUSEN, GERMANY.

ASH-DISCHARGE DEVICE FOR FURNACES.

1,405,029.

Specification of Letters Patent.

Patented Jan. 31, 1922.

Application filed September 18, 1919. Serial No. 324,720.

(GRANTED UNDER THE PROVISIONS OF THE ACT OF MARCH 3, 1921, 41 STAT. L., 1313.)

To all whom it may concern:

Be it known that I, HARRY STEHMANN, a subject of the German State, and resident of Berlin-Hohenzonhausen, Germany, have 5 invented certain new and useful Improvements in Ash-Discharge Devices for Furnaces, (for which applications for patents have been filed in Germany, May 3, 1917; Austria, June 11, 1919; Switzerland, 10 June 12, 1919, and Norway, June 17, 1919, and for which a patent was granted in Germany January 10, 1921,) and do hereby declare the following to be a full, clear, and exact description of the invention, such as 15 will enable others skilled in the art to which it appertains to make and use the same, reference being had to the accompanying drawings, and to letters or figures of reference marked thereon, which form a part of 20 this specification.

This invention has for its object to provide for airtight closing of the discharge devices in use with shaft-furnaces and the like, which are operated under forced draft 25 by compressed air.

The trouble in these shaft-furnaces, operated under wind pressure, lies in the fact that large quantities of dust and grit are blown through the leaky closing contrivances, such as dampers, registers and the like, into the working room beneath the discharge so as to render the atmosphere therein insupportable for the workmen; in addition the machines in the work room become covered with dust not to count the considerable loss of wind. That is why, in spite of heavy counter-weights, the known shutting devices in form of registers and dampers have proved to be unsuitable in the 40 operation of shaft furnaces.

By the present invention the dust tight closing of the discharge pipes in use with shaft-furnaces is effected and all inconveniences and difficulties are overcome, thus 45 ensuring a progress of extraordinary importance.

Back of this invention lies the thought of also rendering available the wind pressure itself in conjunction with the dust for ensuring airtight sealing. This idea is realized by providing in the discharge pipe, 50 ground-in closing contrivances, such as conical valves which, until being compul-

sorily released, are pushed down into their seats by means of compressed air, while 55 being in addition thereto hermetically covered over by a layer of outgoing material, blown there against. The whole of the upper valve surface becomes covered by a dense layer of dust, which to an increasing 60 degree contributes to the complete sealing. This is a new and characteristic means for closing the discharge-pipes in shaft-furnaces, working with coarse, gritty and at the same time with finely pulverized materials. Thus the closures are securely pushed onto their seats by wind pressure and 65 covered over by dust, whereas in use with the registers, known theretofore, particularly when their sliding grid plates were 70 worn out, the wind increased the leakage, blowing through the gaps large quantities of dust, which filled up the room beneath. According to the present invention the material, which is to pass out, becomes lodged 75 on the valve surfaces, thus automatically contributing to more effective sealing. The finely pulverized material can no longer be blown out through the gaps and a deformation of the closing devices as in use with 80 dampers, registers and the like can no longer occur.

The simplest form devised for this purpose is a valve disk, conically inserted or preferably ground-in into adequate valve 85 seat, the surface whereof has a conical or sloping shape with a view to the easy withdrawal and sliding down of the material. For the removal of obstructive elements, which might be deposited on the seats, when 90 the closing contrivances are moved thereto, steel brushes, felts or the like, are arranged to move in advance of the valve and are preferably arranged at the lower-extremities of such valves. These cleaning devices are 95 slightly larger than the lower conical portion of the valve disk and spring back to their normal position after having skimmed over the valve seat, cleaning it at each opening and closing movement.

It is preferred to build the conduit pipe so that the several valve chambers form a sequence, arranged in steps and below each chamber is an inclined sliding surface or funnel. The device may, however, be so made 105 that, in case of the closing contrivances be-

ing opened an uninterrupted lower sliding or chute surface may be arrived at.

As a rule, two ground-in valves which are alternately raised or lowered, will do. The 5 valve in the rear may be coupled up with a third shutting device, something like a simple damper, of known construction bearing against the extremity of a projecting inclined plane, on the conduit. The arrangement 10 should preferably be so made that the damper shuts preparatory to the valve moving onto its seat, in order to prevent the outgoing material from passing out prematurely. When the valves are opened they are 15 withdrawn into valve receiving boxlike chambers arranged above the conduit.

The accompanying drawing illustrates diagrammatically a vertical section of a plant embodying the invention.

20 The material passing down from the shaft of the furnaces falls into collecting funnel *a* into which the air-pipe *b* also discharges. The inclined outlet of the funnel is provided with a damper *c*, of the flat type bearing 25 when closed against an offset *e'* formed by the extremity of the sloping plane *e*. Joined to the closing device as described above are two box-like valve chambers *d* and *f*, and below the chambers in the conduit are outlet 30 conical valve seats *g* and *h*, on which conical valve disks *i* and *k* seat. The top faces of the valves *i* and *k* are inclined relative to their seats, the inclination being greater than the angle of repose of the material to be 35 discharged for ensuring a free gliding down of the material resting thereon, while at the same time allowing the valves to be easily raised. The valves are securely pushed by the wind pressure onto their conical seats 40 and besides they are hermetically covered over by a layer of outgoing material, blown there against. This has the effect of completely closing the chamber and preventing the dust from entering into the work room. 45 The lower side of the closing device has arranged thereon a steel brush *m* for cleaning the valve seats.

In the form of construction as represented 50 the several closures are interconnected in such a manner by any known devices, that the valve *k* and the damper *c* are opened and closed at the same time whereas the valve *i* performs an opposite movement. Thus either *c* and *k* are closed and *i* opened, 55 or *i* is closed while *c* and *k* are open. The movement is, however, invariably effected in such a manner that always one valve is forced to its seat by the wind pressure and is covered over by a layer of the outgoing material. 60

The preferred means for operating the valves comprises a rock-arm or lever *n*, pivoted on a standard *o*. The stems *i'*, *k'*, of the valves *i* and *k* respectively are pivotedly 65 connected to the rock-arm *n* on either side of

the standard *o*. The length of the valve stems is such that when the rock-arm is in a horizontal position the valve *i* is seated and the valve *k* is raised from its seat. The damper *c* has an operating arm *c'* fixed 70 thereto and this arm is connected by a link *p* to one arm of a pivoted bell-crank lever *q*, the other arm of the latter being connected by a link *v* to one end of the rock-arm *n*. When the latter is rocked to raise the valve 75 *i* from its seat the valve *k* will be lowered onto the seat and the damper *c* swung against the offset *e*.

The form of construction as shown does of course not exhaust the ways of carrying 80 out the invention; it goes without saying that in its place any other type of closure can be chosen in which the closing appliances are automatically sealed by the effect of the wind pressure and by the outgoing 85 material resting thereupon. Besides the form of the shutting appliances and of pipe conduits can be arranged as required.

Thus by the means described any dust or gritty particles are prevented from entering 90 the work room, and this means a stupendous progress in the construction of shaft-furnaces operating with wind pressures.

I claim:

1. The combination with a furnace having a grate, a chamber beneath said grate and means for supplying air under pressure to said chamber; of a discharge chute for said chamber, a valve for closing said chute arranged to be held on its seat by the air pressure from said chamber, said valve having an upper face inclined relative to its seat when in closed position, the inclination of 100 said face being greater than the angle of repose of the material to be discharged, whereby upon opening said valve the material thereon will automatically discharge therefrom.

2. The combination with a furnace having 110 a grate, a chamber beneath said grate and means for supplying air under pressure to said chamber; of a discharge chute for said chamber, a plurality of valve seats in said chute, valve receiving chambers extending 115 from the chute, and valves arranged to be wholly withdrawn from said chute into said chambers when opened or held to said seats by air pressure in said first mentioned chamber and chute.

3. The combination with a furnace having a grate, a chamber beneath said grate, means for supplying air under pressure to said chamber and means for closing the bottom 125 of said chamber; of an inclined chute extending from said closing means, two valves arranged and operatively connected for alternately closing and opening said chute, the lowermost valve positively connected to said closing means and simultaneously oper- 130

ated therewith, said valves held to their seats by the air pressure in the first mentioned chamber and chute.

4. The combination with a furnace having a grate, a chamber beneath said grate, a flap damper for closing the bottom of said chamber, and means to supply air under pressure to said chamber; of an inclined chute extending from said damper and chamber, 10 valve chambers extending from said chute, conical valve seats in the chute below said valve chambers, valves arranged to be withdrawn into said valve chambers when opened and having surfaces on their tops inclined 15 relatively to their seats when closed, and valve seat cleaning devices on the bottoms of said valves, the lowermost valve arranged and connected to operate simultaneously with said flap damper.

20 5. The combination with a furnace having a grate, a chamber beneath said grate and means for supplying air under pressure to

said chamber; of a discharge chute for said chamber, a valve for closing said chute having an upper face inclined relatively to its 25 seat and directed toward said chamber, said face operating to hold the valve on its seat when closed by the air pressure and the material in the chute acting thereon.

6. The combination with a furnace having a grate, a chamber beneath said grate and means for supplying air under pressure to said chamber; of a discharge chute for said chamber, a valve for closing said chute arranged to be held on its seat by the air pressure from said chamber, its own weight and the weight of the material. 30 35

In testimony that I claim the foregoing as my invention, I have signed my name in presence of two subscribing witnesses.

HARRY STEHMANN.
